FORM FOR MAKING RUBBER GARMENTS

Abraham N. Spánel, Rochester, N. Y.

Application February 12, 1936, Serial No. 63,548

4 Claims. (Cl. 18—41)

This invention relates to forms on which latex garments such as latex pants or latex bathing trunks may be deposited.

This application is a continuation in part of 5 applicant's copending application, Serial No. 738,669 filed August 6, 1934, now matured into Patent No. 2,086,481, dated July 6, 1937.

When rubber garments such as pants or bathing trunks are made of relatively thin material 10 it is difficult to conceal the contour of different portions of the body covered thereby. This difficulty accounts for the fact that up to now no one has commercialized men's swim trunks made of latex. For this reason prior rubber trunks 15 were made of rather thick rubber, with cemented seams in their construction, so that the garment was necessarily bulky and crude looking. Moreover, they trapped water easily and thereby impeded a swimmer's progress. In diving, the 20 seams often gave way, denuding the swimmer.

In accordance with a main feature of the present invention, there are provided novel forms on which latex can be deposited to produce seamless garments each having on at least a portion 25 of one of their surfaces a raised pattern which conceals the contour of certain portions of the wearer's body covered thereby.

Various other features and advantages of the invention will appear from the detailed description 30 and claims when taken with the drawings in which Fig. 1 is a front elevation of a garment such as a pair of trunks made in accordance with the present invention; Fig. 2 is a side elevation of the same; Fig. 3 is a vertical section taken on the line 3—3 of Fig. 2 looking in the direction of the arrows, and illustrating how the inner surface of the crotch portion of the trunks is provided with a raised pattern; Figs. 4 and 5 are fragmentary sections through the 35 trunks taken respectively on the lines 4—4 and 5—5 of Fig. 1; Figs. 6, 7 and 8 show different styles of raised patterns that may be applied to the inner surface of the crotch portion of the trunks instead of the pattern shown in Fig. 3; Fig. 9 is a fragment of a pair of trunks showing how substantially all of the inner surface thereof 40 may be provided with a raised pattern; Fig. 10 shows a modified construction of the trunks in which the front margin of the leg portion thereof is shorter than the rear margin; Fig. 10a 45 is a fragmentary view illustrating an alternative leg construction for the trunks; Fig. 11 is a plan view of a form on which a pair of rubber trunks made in accordance with the present invention 50 can be deposited; Fig. 12 is a vertical section 55

somewhat enlarged of this form with a fragment of the trunks shown in the position in which they are deposited thereon, said section being taken substantially on the line 12—12 of Fig. 11; Fig. 13 is a fragmentary view partially in section showing a slightly different surface contour at the crotch portion of the form; Fig. 14 is a fragmentary vertical section illustrating a somewhat different surface contour at the crotch portion of the form; Fig. 15 is an enlarged cross-sectional view of the form with the trunks thereon, taken substantially on the line 15—15 of Fig. 11; Fig. 16 is a further modified type of form on which the surface corrugations are concentrically arranged with respect to the crotch 15 of the form; Fig. 17 is a vertical section of this form taken substantially on the line 17—17 of Fig. 16, a part of the leg portion of the form as well as a part of the leg of the trunks deposited thereon, being broken away; Fig. 18 is 20 a front view of a still further modified type of form in which the surface corrugations thereon radiate generally from the crotch portion of the form; Fig. 18a is an alternative shape for the leg portion of the form of Fig. 18; Fig. 19 is a 25 fragment of a further modified type of form in which the surface thereof about the crotch, instead of being broken up by corrugations, is broken up by a plurality of small circular depressed areas; Fig. 20 is a fragment of a still 30 different type of form of which the entire surface is broken up by a series of intersecting line cuts whereby the entire surface of the garment-generating portion of the form, is provided with a surface pattern; and Fig. 21 is a 35 front elevation and Fig. 22 is a side elevation of a fragment of a form similar to that illustrated in Fig. 11, said form being adapted to generate trunks having the front margin of the legs offset with respect to the rear margins thereof, as shown in Fig. 10.

In Fig. 1, there is disclosed a pair of pants or trunks 5 having a body portion 6 and legs 7. These trunks, which are made of liquid latex, have their margins at the waist opening and 45 the leg openings therein reinforced preferably by integral ridges of latex, designated 6a and 7a. It has been discovered that abbreviated pants or trunks must be provided with more fullness of the material at the back than at the front thereof, 50 since the buttocks of the wearer owing to its greater area requires more material for coverage. In order to afford this necessary fullness on such abbreviated trunks, the rear margin b of the trunk at the waist opening is extended 55

beyond or offset with respect to the front margin *a* at said waist opening. Also the free edges of the legs are inclined upwardly and outwardly from the vertical axis of the trunks to afford 5 the necessary coverage in an abbreviated garment. It is particularly desirable, especially in trunks for men, to provide more room afforded by the outwardly bulged region *9* adjacent the crotch portion of the trunks.

10 Since the latex of the trunks is relatively thin it clings intimately to the body of the wearer, so that the contour of certain portions of the body would normally be disclosed therethrough to the embarrassment of the wearer. It has been 15 discovered that if one surface of the trunks, is provided with an uneven surface pattern such as a series of ridges and depressions, the contour of the portion of the body covered thereby will not be revealed. As shown in Figs. 3, 4 and 5 20 the pattern may comprise a series of vertical ridges *10* separated by depressions *11*, provided on the inner front surface of the trunks at the crotch portion thereof. This ridging may be applied to any part of the trunks as well as to 25 the crotch portion.

As shown in Fig. 6, the ridges and the depressions may be generally concentric with the outline of the crotch portion or they may radiate from the crotch portion as illustrated in Fig. 7.

30 The raised pattern may also be developed by a series of hemispherical protuberances *12* (Fig. 8) or by a series of intersecting ridges *13* (Fig. 9). The raised pattern, although preferably localized at the crotch portion of the trunks, may extend 35 over the entire area of the inner surface thereof as shown in Fig. 9. Obviously, by turning the trunks inside out, the pattern will be on the outside and serve the same purpose.

The trunks *5* illustrated in Fig. 1 may be further modified as disclosed in Fig. 10 by having the 40 lower front margin of each leg *7* offset with respect to the lower rear margin thereof. In the present disclosure the front margin is shorter than the rear margin, although the reverse of this condition may be established without departing from the invention. As illustrated in Fig. 10a, the margins of the legs *7* can be inclined 45 upwardly and outwardly as well as having the front and rear leg margins offset like in Fig. 10. This arrangement can replace the leg construction 50 of Fig. 1.

The trunks disclosed in Fig. 1 may be made on the form *20* illustrated in Fig. 11. This form which is composed of aluminum, stainless steel or the like, has the general outline of the desired trunks. It will be noted that the portions *21* of the form, swell outwardly to provide room in the trunks to accommodate the hips of the wearer, while the top portion of the form, which generates 55 the waist opening in the trunks, terminates at an abrupt edge *22* in the surface of the form. This form includes leg-generating portions *23*, each of which terminates in a projecting plate *24* having an abrupt edge *25*. It has been mentioned 60 that the trunks adjacent the crotch thereof bulge outwardly to provide room for the body parts of the wearer. This bulge is generated in the trunks by a protuberance *26* on the form best illustrated in Fig. 12 or by a cavity *27* as illustrated in Fig. 13, although if no bulge is desired in the trunks, the protuberance or the cavity may be dispensed with, as illustrated in Fig. 14. In order to provide a 65 raised pattern on the inner surface of the trunks at the bulged crotch area, a series of vertical depressions *28* and ridges *29* are provided in the 70

75 form as indicated in Figs. 11, 12, 13 and 14. The upper end of the form is provided with a fin *30* by which the form can be supported in a rack (not shown) in inverted position with respect to its position as illustrated in Fig. 11.

The form in the inverted position has a coating of latex, deposited thereon, as illustrated in Figs. 12 and 15. During the deposition of the latex on the form and the draining of the same, the latex will accumulate just above the abrupt edge *22* 10 as a reinforcing ridge *6a* which is substantially semi-pear shaped or semi-oval in cross section. In the junction between the plate *24* and the end of the leg *23*, the latex will accumulate as a reinforcement *7a* which is generally triangular in 15 cross section. However, at the abrupt edge *25* of the plate *24*, there will be a region of weakness in the deposited layer at which the layer can be parted to remove the excess latex on the remainder of the form after the latex has "set". 20 During the deposition of the latex on the form, thickened ridges *10* will develop in the depressions *28* while at the ridges *29* of the form, the layer will have a coating indicated at *11* in Fig. 15. After the layer has been suitably "set" the excess portion thereof (not shown) upon the upper and the lower ends of the form are stripped away as far as the abrupt edges *25* and *22* in Fig. 12 after which the trunks can be removed from the form and prepared for the trade in the usual 25 manner.

The form illustrated in Fig. 16 differs from that illustrated in Fig. 11 in that the legs *23* terminate at abrupt edges *36* while the portion of the form which generates the waist opening 30 is provided with a projecting plate *37* terminating in an abrupt edge *38*. The raised pattern at the crotch area of this form comprises a series of depressions or grooves *57* and a series of ridges *58* concentrically arranged with respect to the 35 crotch proper. The crotch portion of the form, may have a protuberance similar to that illustrated in Fig. 12 or a concavity similar to that illustrated in Fig. 13 or may be a straight portion 40 as shown in Fig. 14. In Fig. 16, the leg portions 45 of the form are provided with fins *39* by which the form can be supported, in the position illustrated, on a suitable rack (not shown) and by which the form is carried during the dipping or 50 depositing operations.

As a result of depositing latex on this last-mentioned form, a coating of latex *5* adheres to the surface of the form (Fig. 17). At the junction between plate *37* and form proper, the latex accumulates as indicated at *6a* while at the abrupt edge *38* of the plate, a region of weakness is developed in the layer so that when the excess latex on the top of the plate *37* is removed, the reinforcement *6a* remains with a torn or feather edge *6b*. Above the abrupt edge *36* of the leg 55 portions the latex layer accumulates as indicated at *7a* as a reinforcing ridge which is generally semi-pear shaped or semi-oval in cross section. At the abrupt edge *36* itself a line of weakness is developed in the layer so that the excess latex (not shown) on the lower end of the leg portion can be readily stripped away as far as this line of weakness. In the grooves *57* on the crotch area of the form, the latex will accumulate as a series of concentric ridges *44* separated by valleys *45* 60 generated by the ridges *58* of the face of the form.

The form illustrated in Fig. 18 is similar to that illustrated in Fig. 16, except that the raised pattern at the crotch portion, consists of a series of 65

radiating depressions 46 cut into the face of the form leaving triangular areas 47 in the plane of the general surface of the form. This form also has the leg portions 23 of the form cut off so that the plane of these end portions is inclined upwardly from rear to front so that a garment similar to that of Fig. 10 can be made thereon. This form also has the projecting top plate 37 inclined downwardly from the rear surface of the form to the front surface thereof so that trunks deposited thereon will have their margins at the waist opening offset, the rear margin projecting beyond the front margin. As will be seen from Fig. 18a, the plane of the end of each leg portion 23 of the form can be inclined upwardly and outwardly as well as from rear to front so that the trunks of Fig. 10a can be made thereon.

As illustrated in Fig. 19 the raised pattern at the crotch area of the form may consist of a series of generally hemi-spherical depressions represented by the circles 49.

Instead of having the raised pattern localized on any particular portion of the form, it may be distributed over a substantial portion or even over the entire surface article-generating portion of the form. This raised pattern may consist of a series of depressions defined by a plurality of parallel line cuts 50 into the surface of the form intersected by other parallel line cuts 51 as disclosed in Fig. 20.

The form of Fig. 11 may be modified as illustrated in Figs. 21 and 20 by having the plane of the end portions of the legs inclined upwardly from rear to front as well as outwardly and upwardly so that the front margin of the leg is shorter than the rear margin. The leg portions 23 of this form terminate in a projecting plate 52 which is provided with an abrupt edge 53.

It should be particularly noted that the ridges 40 on the form which generate the surface pattern

on the garment, are rounded in cross section so that the garment-generating surface of the form is devoid of any abrupt edges. This is essential since an abrupt edge on the form would develop thin regions in the garment.

The present disclosure is given merely by way of example and it will be understood that there can be many modifications and variations therein within the scope of the appended claims without departing from the spirit of the present invention.

What I claim is:

1. A form for making latex trunks or the like, said form being provided with a body portion and leg portions thereon to define a crotch, said body portion having a protuberance with an uneven surface thereon at said crotch.

2. A form for making latex trunks or the like, said form being provided with a body portion and leg portions thereon to define a crotch, said body portion having a cavity formed therein at said crotch, the surface of said cavity being uneven.

3. A form on which latex garments can be deposited, said form comprising a body portion and leg portions to define a crotch, a localized area of the garment-generating surface adjacent the crotch portion of the form being interrupted by a plurality of spaced projecting portions generally rounded in cross section whereby an uneven pattern of projections and depressions will be produced on a surface of the latex deposited on said area.

4. A form for making latex trunks or the like, said form being provided with a body portion and leg portions thereon to define a crotch, said body portion at said crotch having a rounded offset portion to define a bulge in the resulting trunks, the rounded offset portion having its surface interrupted by rounded projections.
